VEGETABLE JUICING MACHINE OR SIMILAR ARTICLE

Lloyd D. Slagell, Peoria, Ill.

Filed Sept. 26, 1960, Ser. No. 62,264

Term of patent 14 years

(Cl. D89—1)

Figure 1 is a front elevational view of a vegetable juicing machine or similar article, showing my new design.

I claim:

The ornamental design for a vegetable juicing machine or similar article, as shown.
